United States Patent Office

Des. 175,228
Patented July 26, 1955

175,228

CUFF LINK WATCH OR SIMILAR ARTICLE

Jacques Meyer, Paris, France, assignor to Arthur E. Manheimer, Chicago, Ill.

Application March 23, 1954, Serial No. 29,665

Term of patent 3½ years

(Cl. D17—7)

Fig. 1

Figure 1 is a front elevational view of the cuff link watch or similar article showing my new design; and

The characteristic feature of the design resides in the portions shown in full lines.

I claim:

The ornamental design for a cuff link watch or similar article, as shown and described.
